Julius Hatch

Aug 17, 1835

The Schedule referred to in these Letters Patent and making part of the same containing a description in the words of the late Julius Hatch himself of his improvement in the Machine for sowing plaster, lime and ashes.

Be it known that I Julius Hatch of Great Bend, Lycoming County, Penn. have made an improvement in the machine for sowing plaster, lime and ashes which is described as follows: The machine consists of two or four wheels a common axle tree or axle trees, and a pair of shafts for the purpose of moving the machine whatever wanted thrown out of gear, a band or cog wheel on the inside of one of the wheels in its hub, a revolving shaft with a pinion or whirl, working at one of its ends, and a crank at the other placed under the shafts, a longitudinal rod passing from the crank to an elbow, formed of a right angle placed under one of the shafts, a horizontal rod from the elbow, an arm fastened by a pin, on the axle tree, a sliding rod with its teeth at the bottom of the angular box, the angular box itself, its regulating gauge with thin screws on which the sliding rod rests, a double apron to prevent the plaster flying about, the drivers seat, and the fenders on the sides of the shafts. The wheels, the axle tree, & the shafts for moving the machine or apparatus are of the ordinary construction as are also the bands or cog wheel placed against it fastened to the hub of the wheel and its pinion or whirl & revolving shaft, and their position common to various seed machines.

The revolving shaft is placed under the shafts (and) is parallel, and a suitable distance from, the axle tree and behind the angular box. The first mentioned rod connected by a crank at the end of the revolving shaft runs parallel to one of the horse shafts. The elbow is formed of two sides producing a right angle. The horizontal rod connected with the middle arm

arm of the elbow, runs to the arm. The arm is fastened at one end by a pin or screw to the axle tree which is its fulcrum, its other end is ^{secured} by a staple or otherwise & is fastened about the centre of the sliding rod. The angular box for the reception of the plaster &c is formed of two sides about 18 inches deep, each, and are about 14 inches apart at top. They are confined at their ends by angular pieces of wood and at suitable distances, inside are angular pieces running partly down towards the bottom of the sides, not only to strengthen the box but to permit the plaster &c to pass underneath. The lower sides of the angular box are regulated by the screws to suit the nature of the matter to be distributed. The box may have a cover for protection from the weather. It is partly suspended ^{by} the shafts &c in front of the driving wheels. The sliding rod is placed beneath the sides of the box and has teeth placed at suitable distances apart to agitate the plaster &c. The regulating gauges are fastened by screws to the sides of the box, and a screw to the ends of every couple of gauges placed at suitable distances apart the whole length of the box (inside or before the aperture at the lower sides of the box). The double apron for preventing the flying off of the plaster &c is suspended from the lower side of the box to within a suitable distance of the ground. In some cases the apron may be suspended with. The driver's seat is placed on inclined arms fastened on the upper side of the axle tree, running back, to preserve the equilibrium of the machine and for the driver's convenience. The feeders are bent pieces of wood which are fastened about the middle of the outer part of each shaft & run to each end of the box, and their object is to protect the angular box from injury. This arrangement for a cart fixture can be adapted to a waggon when the circumstances demanded for extensive operations. By mixing clover or ^{timothy}

Twenty seed with plaster, lime, ashes or earth, the seed may be spread in a proper manner. Operation. The hand or moving power being applied to the shaft, and set in motion, the supporting wheels revolve, each of which turns a cog or hand wheel secured thereto by pins or screws, this hand or cogwheel works in connection with a pinion on which wheel is fastened securely at one end of the revolving axle. As the axle revolves, it turns the crank at its end, which moves the crank rod & the elbow which communicates the motion to the arm. The arm being secured to the sliding rod moves it to and fro horizontally, which agitating the plaster & causes it to fall to the ground. For further illustrations of my invention Refer to the model and drawing, in the Patent Office. What I claim as my invention and for which I solicit a Patent is the arrangement and adaptation of the crank, crank rod, elbow & horizontal rod, arm and sliding rod with its teeth together with the regulating gauges, as described in the foregoing specification of this machine for sowing plaster, lime, and other
